UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

CURRENT COLLECTOR AND SLEET REMOVER.

Application filed March 26, 1923. Serial No. 627,603.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in a
Current Collector and Sleet Remover, of
which the following is a specification.

My invention relates to a current collector
10 for engaging an overhead trolley conductor
or other conductor by means of which cur-
rent may be transmitted to a moving vehicle.

The object of my invention is to produce
a device which will not only collect the cur-
15 rent from the conductor supplying energy,
but will also clean the conductor of sleet or
snow which interferes with the contactor
engaging directly with the conductor.

My invention resides in the new and novel
20 construction, combination and arrangement
of the various parts hereinafter more fully
set forth and described and shown in the
accompanying drawing.

In the accompanying drawing:

25 Fig. 1 is a side view in elevation of my
invention represented as engaging a con-
ductor and as secured to the upper end of a
trolley pole, the lower end of which is se-
cured to the moving vehicle in any of the
30 well known ways, but which is not shown
here as it forms no part of my invention.

Fig. 2 is an end view in elevation of Fig. 1.

Fig. 3 is a sectional view on the line 3—3
35 of Fig. 2.

Fig. 4 shows schematically the relation
which my invention takes with respect to
the conductor, as my invention is moved
40 along the conductor by means of the mov-
ing vehicle.

45 In the preferred embodiment of my in-
vention I employ a body member 1 provided
with a socket portion 2 to receive the end of
the pole 3. The pole is held in engagement
and relation with the socket member 2 by
means of the pin 4. The body member 1 is
also provided with oppositely disposed lugs
5—5 spaced apart, and provided with a re-
cess therethrough to receive a pin 6. The
pin 6 is held in position by means of cotter
pins 7—7 although other well known means
50 may be substituted. Mounted on the pin
6 and between the lugs 5—5 is a member 8
arranged to rotate upon the pin 6, and to

form therewith a roller bearing for the cur-
rent collecting member 9.

55 The collecting member 9 is mounted upon
the pin and sleeve 6 and 8 and between the
lugs 5—5 and is provided with a V or U
shaped groove 10 whereby the member 9 is
prevented from side displacement with re-
spect to the conductor 11. The member 9
is not circular as is the case with the ma-
jority of the current collecting members in
common use, neither is the periphery of the
groove 10 which is semi-circular at its op-
posite ends, but is elongated and the mem-
ber 9 is provided with an elongated slot 12
through which passes the mounting 6—8 and
this permits the member 9 to not only rotate
with respect to the body member 1, but to
move in a longitudinal direction and rela-
tive thereto. The member 9 is also pro-
vided with the openings 13—13 from the
apex of the groove 10 through to the slot 12.
The apex of the groove 10 between the ex-
treme ends thereof is displaced as at 14 on
70 opposite sides of the longitudinal diameter
of the member 9, and this tends to permit
loose particles of snow or ice to be forced
out of the groove 10 much more readily
than otherwise.

75 The operation of my invention is as fol-
lows—

Referring to Fig. 3, there are shown six
80 schematic views of the current collecting
member 9 and the mountings therefor,
namely; the pin 6 and sleeve 8. These mem-
bers 9, 6 and 8 are shown in relation to the
conductor 11 as the current collector 9 moves
85 along the conductor 11 due to the movement
of the vehicle upon which it is mounted.
Assuming that the member 9 is in engage-
ment with the conductor 11 as shown by the
position A, and the members 6 and 8 are
90 in the position shown with relation to the
member 9, and if the vehicle is moved with
respect to the conductor thereby moving the
member 9, the same will rotate about its sup-
ports 6 and 8, and after it has moved a cer-
tain distance it will assume the position
95 shown at B. As the movement of the mem-
ber 9 is continued due to the movement of
the vehicle, it will assume a position with
respect to the conductor as shown at C, and
further forward movement of the vehicle will
100 finally bring the member 9 with respect to the

conductor in the position shown at D. It will be noted that the mountings 6 and 8 are now at the opposite end of the slot 12, and during the travel of the member 9 from its 5 position as shown at A to the position as shown at D, the member 9 is rotated about the pin 6 and sleeve 8. As the member 9 moves forward still further from the position shown at D, the pin 6 and sleeve 8 10 merely slide forward in the groove 12 without moving the member 9 until it reaches the right hand end of the groove and assumes a position as shown at A' which corresponds with that of the position A. The 15 axis of rotation has thus been changed from one end of the slot 12 to the other end of the slot. Further forward movements of the member 9 will only cause repetitions of the conditions shown at B, C and D; and it 20 will be noted that the position B' corresponds with that position shown at B.

The effect of the rotating movement of the elongated member 9 about the pin 6 and sleeve 8 tends to produce an impact or hammer blow upon the conductor 9 at each half revolution of the member 9 relative to the pin 6 and sleeve 8; and as this impact or hammer blow is very severe and rapid, it sets up a sufficient vibration in the conductor 25 to break up the sleet thereon and cause the same to drop from the conductor. The effect is exactly the same as though one were to hit the conductor with a hammer or heavy stick while the conductor was laden with 30 sleet. The operation of my invention is the same whether it is moved forward or backward.

It will, therefore, be seen that my invention acts not only as a collector for currents from the conductor, but also acts as to 40 remove sleet therefrom and might be termed an anti-sleet current collector, and may be used to act as a current collector, or a sleet remover, or as both in combination.

45 There are, of course, modifications which will suggest themselves to those skilled in the art after reading my disclosure, and therefore, I do not wish to be limited otherwise than by my claims.

50 I claim:

1. An article of manufacture comprising a support and a member mounted thereon to apply an impact blow to a conductor periodically as the member is moved continuously along the conductor in the same direction.

60 2. An article of manufacture comprising a support and a member mounted thereon to rotate relative thereto and having a period of rest as to rotation between each half revolution as the member is moved continuously along a conductor in the same direction.

65 3. An article of manufacture comprising a support and a member mounted to rotate

thereon and to engage a conductor and to impart to the conductor an impact blow at each half revolution of the member as the member is moved continuously along the conductor in the same direction.

70 4. An article of manufacture comprising a support and a member mounted to rotate thereon and engage a conductor and rotate relative to the conductor and to remain substantially at rest relative to the conductor between each half revolution of the member as the member is moved in a continuous direction along the conductor.

75 5. An article of manufacture comprising a support and a member mounted thereon to rotate relative thereto and to engage a conductor and to rotate relative thereto, the rotation of the member relative to the conductor comprising alternate periods of rotation and rest as the support moves longitudinally to the conductor in the same direction.

80 6. A current collector comprising a support and a member mounted thereon to rotate relative thereto and to engage and move along a conductor, and means permitting the axis of rotation of the member relative to the support to shift as the support and member are moved along the conductor.

85 7. An article of manufacture comprising in combination a support and a member rotatably and slidably mounted thereon and arranged to impart an impact blow to a conductor along which the member is moved.

90 8. An article of manufacture comprising in combination a support, a member mounted thereon and means on the member engaging means secured to the support to permit the member to rotate relative to the support and to shift the axis of rotation of the member relative to the support.

95 9. An article of manufacture comprising in combination a support, a member mounted thereon and provided with an elongated slot, means passing through the slot to secure the member to the support and permit it to rotate relative thereto.

100 10. An article of manufacture comprising in combination a support, a member mounted thereon and provided with an elongated slot, means passing through the slot to secure the member to the support and permit it to rotate and slide relative thereto.

105 11. A current collecting member provided with a groove to receive a conductor in slideable relation thereto, an elongated slot and a circular bearing member passing through the slot and mounted in a support.

110 12. An elongated current collecting member provided with a groove, the opposite ends of the groove being semi-circular, an elongated slot symmetrically disposed with respect to the groove and means passing through the slot and mounted in a support.

115 13. An elongated current collecting mem-

ber provided with a groove to receive a conductor, the opposite ends of the groove being semi-circular and the intermediate portions of the surface of the groove depressed, an 5 elongated slot symmetrically disposed with respect to the groove and means passing through the slot and mounted in a support.

14. A current collector and sleet remover comprising a support, an elongated member: 10 mounted thereon to rotate relative to a conductor and to engage the conductor and to impart a succession of impact blows to the conductor as the member rotates in the same direction.

15. A current collector and sleet remover comprising a support, an elongated member,

mounted thereon to engage a conductor and to impart a succession of impact blows to the conductor as the member is moved along the conductor in the same direction. 20

16. An article of manufacture comprising an elongated member mounted in a support to rotate relative thereto and having a groove to engage a conductor, the groove having its opposite ends semi-circular and the intermediate portions depressed, an 25 elongated slot in the member, means passing through the slot to secure the member to the support and openings from the grooves leading to the slot for the purpose described. 30

In testimony whereof I affix my signature.
SAMUEL S. MATTHES.
